EXERCISER

Noël Ouellette, Montreal, Quebec, Canada
Application December 6, 1954, Serial No. 33,416
Term of patent 7 years
(Cl. D83—1)

The other side is like the side shown, and the back is substantially plain.

I claim:

The ornamental design for an exerciser, as shown and described.
